ROBERT W. BANKS, OF EL DORADO, ARKANSAS

JARRING DEVICE FOR PUMP STRUCTURES

Application filed June 15, 1927. Serial No. 199,082.

This invention relates to an attachment for pump structures and more particularly to the novel construction of disengaging jars, and has for its primary object the provision of a device particularly adapted for oil and water wells for jarring loose sucker rods, pipes, pumps, pump plungers, and other devices which may become stuck in a well, brought about by conditions well known in this particular industry.

Another object of the invention is the provision of a device that can be connected to an end of a string of sucker rod and to the top of a pump or pump structure to remain inactive under normal conditions, but capable of being immediately rendered active upon the well sanding up or the pump or pump plunger becoming clogged with sand or other foreign matter.

Another object of the invention is the novel design and connection of the parts and operation thereof whereby time, labor and material may be saved and the expense connected with the pulling up of tube casings or other devices eliminated.

Besides the above my invention is distinguished in the construction of a device that may be very readily incorporated in pump structures commonly in use and which when in place will not interfere in any way with the proper operation of the various structures or drilling devices.

A feature of the invention is the construction and association of the various parts for full protection against sand, water or other matter coming in contact therewith.

An important feature of the invention is the design and mode of connection of the various parts so that all joints or connections are visible for proper inspection thereby eliminating the possibility of accident or obstruction of the well due to improper or weak connections.

With these and other objects in view, the invention will be better understood from the following detailed description taken in connection with the accompanying drawings wherein:

Figure 1 is a side elevation of the device; Figure 2 is a similar view with certain

parts disconnected and certain parts in section;

Figure 3 is a vertical sectional view of the barrel;

Figure 4 is a vertical sectional view of the device;

Figure 5 is a sectional view on the line 5—5 of Figure 4, and

Figure 6 is a detailed view illustrating the engagement between the clutch members.

Again referring to the drawings, illustrating one of the many constructions of my invention, the numeral 1 designates a pump structure, which may be of any usual design now on the market constructed to be operated by a line of sucker rods 2. My improved jar device 3 is interposed between the sucker rods 2 and the pump structure and so designed as to provide a rigid connection between the pump structure and the sucker rods 71 under normal conditions, but under abnormal conditions capable of being adjusted so as to subject the pump structure to a jarring action or to completely disengage the sucker rods from the pump structure.

To accomplish this desired result, I provide a lower connector 4 having a female threaded section 5 for direct engagement with the pump structure. This connector 4 is further provided with a male threaded section 6 the threads of which being of left hand formation to engage correspondingly shaped threads in a female section 7 formed on an intermediate connector 8. This intermediate connector 8 is also provided with a threaded male section 9, engaging the threads carried by the lower end of a barrel 10. The upper end of this barrel 10 has screw threaded engagement 11 with a third connector 12 hereinafter known as the upper connector directly screw threaded to the usual line of sucker rods designated by the numeral 2. Each of these connectors are provided with flattened surfaces 13 to facilitate the application of a tool.

A jar rod 14 has its lower end detachably connected to and extends axially from the lower connector 4, and slidably received in the connector 8 and also in the barrel 10. The lower connector 4 is provided in its upper

end with an axial recess 4^a having screw threads of left-hand formation, and the lower end of the jar rod 14 is similarly screw threaded and engaged in the recess. This rod 14 has fixedly secured thereto a head 15 slidably arranged within the barrel and engageable with the shoulder 16 provided by the member 9 to limit the relative reciprocatory movements of the rod and barrel and to provide the proper jarring action for disconnecting the pump structure or other devices from their engagement with the well structure.

As far as I have proceeded, it will be appreciated that when the female section 7 has screw threaded engagement with the male section 6 a rigid connection is provided between the pump structure and the sucker rods by means of the barrel 10, thereby rendering the jarring device inactive, but upon disengagement of the female section 7 with the male section 6, which may be accomplished by turning the sucker rods 2 to the right, a loose connection is provided between the sucker rods and the pump structure to enable the barrel and jar rod to have relative reciprocatory movements for intermittently bringing the head 15 into engagement with the shoulder 16 for providing the proper jarring effects. It is, of course, to be understood that the drilling rig or other type of drilling machinery will be adjusted to accommodate this sliding connection provided between the sucker rods and the pump structure to enable the heads to properly engage the shoulder 16 to create the proper forces to jar the parts loose.

If under exceptional unfavorable conditions the pump structure cannot be dislodged by a jarring action, I have incorporated in my invention a clutch device engageable in a predetermined arrangement of the component parts to completely disconnect the jar device from the pump structure.

There are various ways in which this desired result may be accomplished but for the purpose of illustration, I have shown an ordinary clutch structure the component parts of which are carried respectively by the barrel and the jar rod so as to engage in a predetermined position of the barrel and jar rod. One of the clutch elements 17 is directly secured to the head 15 while the other clutch element 18 is mounted contiguous to the shoulder 16, so that upon the barrel reaching its uppermost position and the jar rod 14 reaching its lowermost position, the clutch elements will interengage to provide a rigid connection between the barrel and the rod so that the two can be turned as a unit when the sucker rods are turned to the right. Due to this connection rotary action of the sucker rods 2 will cause the jar rod 14 to disconnect from the lower connector 4 so that all parts of the jar device, with the exception of said connector, may be quickly

and easily removed from the well. The connectors 4 and 12 are of solid formation. The connector 4 closes the lower end of the connector 8 and the connector 12 closes the upper end of the barrel 10, whereby to prevent the entrance of water and other foreign matter into the barrel and thus insure the proper functioning of the device after the disconnection of the connector 8 from the connector 4.

From the foregoing description taken in connection with the accompanying drawings, it will be appreciated that I have provided a device capable of the dual function of subjecting the pump structure to a jarring action or entirely disconnecting the pump structure from its operating structure. This result is accomplished with a minimum number of parts that are substantially connected together and when connected, completely enclosed so as to be fully protected from sand or other foreign matter.

In concluding, I wish to state that the various parts may be designed and arranged in other relations than illustrated and various other types of clutches and various other constructions or connectors may be utilized for providing a detachable connection between the component parts, therefore, I do not desire to be limited in any manner except as set forth in the following claims.

What I claim as new is:

1. A jar device for a pump structure comprising a connector adapted to be secured to the pump structure, a jar rod detachably secured to the connector by left hand screw threads, a head carried by the rod, a barrel receiving the rod and head, and means connecting the barrel to the connector, said means being secured to the barrel by right hand threads and detachably secured to the connector by left-hand screw threads.

2. A device for a pump structure comprising a lower connector adapted to be secured to the pump structure, an intermediate connector detachably secured to the lower connector and having an axial passage closed by the lower connector, a jar rod passing through the intermediate connector and having its lower end detachably connected to the lower connector, a head fixedly secured to the upper end of the rod, a barrel receiving the rod head and secured to the intermediate connector and having its lower end closed by said connector, and an upper connector secured and closing the upper end of the barrel.

In testimony whereof I affix my signature.

ROBERT W. BANKS.
